UNITED STATES PATENT OFFICE.

MORGAN LEWIS JONES, OF NEATH, WALES, ASSIGNOR OF ONE-THIRD TO JOHN MANGER FELLS AND ONE-THIRD TO WILLIAM HENRY PATCHELL, OF LONDON, ENGLAND.

MEANS OR APPARATUS FOR CLEANING TINNED PLATES.

1,162,070.

Specification of Letters Patent. Patented Nov. 30, 1915.

Application filed September 14, 1914. Serial No. 861,743.

To all whom it may concern:

Be it known that I, MORGAN LEWIS JONES, a subject of the King of England, residing at 12 Green street, Neath, in the county of 5 Glamorgan, South Wales, have invented cer-
tain new and useful Means or Apparatus for Cleaning Tinned Plates, of which the fol-
lowing is a specification.

This invention relates to the cleaning of 10 the surfaces of tin plates after the tinning operation, and has for its objects to provide means or apparatus whereby such cleaning may be rapidly effected in an automatic manner, without liability of the plates bend-
ing or buckling; and so that dust or the like 15 from the granular or pulverulent substance used for cleaning is largely or wholly prevented from access to the atmosphere of the room in which the machine is being 20 operated.

I will describe my invention with the aid of the accompanying sheet of explanatory—and more or less diagrammatic—drawings which illustrate, by way of example only, 25 one mode of embodying same, the novel features or characteristics being pointed out in the several claiming clauses concluding this specification.

In said drawings:—Figure 1 is a side view, 30 mainly in section, and Fig. 2 a transverse view, of the machine. Fig. 3 illustrates a set of conveyer rolls or rollers and electro-magnet, drawn to an enlarged scale as compared with Figs. 1 and 2.

35 *a* indicates a machine frame or standard and *b* the bed-plate thereof, *c* represents the lower and *d* the upper portion of a housing or casing supported on said frame *a*; and *e*, *f*, designate openings or slots arranged in 40 the respective end walls of said housing, through which slots the plates enter and leave the machine.

Horizontally mounted on said bed-plate *b* are a plurality of sets of plate conveyer 45 disks, rolls or rollers *g*, each set of rollers being arranged in parallel disposition between the pole pieces *h* of an electro-magnet (*i* Fig. 3 denotes the magnet coil) but we may substitute permanent magnets for said 50 electromagnets. Said conveyer rollers *g* which extend or project beyond the upper faces of said magnet poles *h* are carried by shafts or spindles *j* revolubly mounted in suitable bearings within said housing or cas-
55 ing, and the whole of the rollers are simul-

taneously rotated by any suitable form of gearing which is, preferably, arranged at a side of the machine. As illustrated, said conveyer rollers *g* are arranged in sets of three, but, obviously, the number of rollers 60 in each set may vary according to the size and output required of the machine.

Between adjacent sets of rollers there are fitted distance or floor plates *n* and below the inverted or depending middle roller and 65 magnet sets is arranged a pocket or trough *k* for the reception of cleaning substance, as bran, and in which pocket a revoluble brush roller *o* is disposed.

l l denote inclined brushing boards, the 70 lower ends whereof are fitted with felt or other suitable brushing materials *l¹*.

In use, bran in heaps *p p* being placed in the compartments *m m* of the housing, and also in hopper *k*, the machine is set in 75 operation, the rollers of the lower sets revolving in one direction, and those of the upper sets revolving in the opposite direction. The tinned plates *n¹* to be cleaned on being fed to the machine are conveyed 80 through same by said rollers to which they “hold” or adhere under the attractive influence of the magnets *i*. The upper faces of the plates *n¹* are brushed clear of the cleaning bran of heap *p p* by the inclined 85 brush boards *l l*, and the under faces are cleaned in passing over hopper or pocket *k* the bran in which is agitated by the brush roller or rollers *o* revolving therein; the inverted or depending magnet sets assist in 90 the conveyance of the plates when passing over said pocket *k*.

In the example illustrated the plates are horizontally fed to the cleaning machine by means of a rotary agitating device *r* and a 95 grid *s* through which the arms of the feeder pass. Such a device, however, is only employed when the plates are delivered by hand to the cleaning machine from the tinning machine. When the plates are delivered by mechanical means from the tinning machine it is merely necessary to provide conveyer rollers and guides by means of which the plates pass directly into the cleaning machine.

Having now described my invention, what I claim as new and desire to secure by Letters Patent is:

1. A machine for cleaning the surfaces of tinned plates after the tinning operation,

comprising a casing having openings at opposite ends, a plurality of sets of plate conveyer rollers in said casing, magnets below the rollers and having pole pieces between the rollers of each set and in a plane below the periphery of said rollers, said casing having the bottom thereof provided with a pocket adapted to contain a cleaning material, and a revoluble brush roller in said pocket.

5 2. A machine for cleaning the surfaces of tinned plates after the tinning operation, comprising a casing having openings at opposite ends, a plurality of sets of plate con-

veyer rollers within said casing, magnetic pole pieces in proximity to the rollers of each set and disposed in a horizontal plane below the periphery of said rollers, said casing having a pocket therein adapted to contain a cleaning material, a revoluble brush roller in said pocket, and an inclined brushing board in said casing.

10 In testimony whereof I affix my signature in presence of two witnesses.

MORGAN LEWIS JONES.
